JOHN STADERMANN AND HENRY SAUERBIER, OF NEW YORK, N. Y.

Letters Patent No. 63,323, dated March 26, 1867.

IMPROVEMENT IN BREAST PROTECTORS.

The Schedule referred to in these Letters Patent and making part of the same.

TO ALL WHOM IT MAY CONCERN:

Be it known that we, JOHN STADERMANN and HENRY SAUERBIER, of the city, county, and State of New York, have invented a new and useful article to be applied to male and female dresses, and which we term a Dress Improver; and we do hereby declare that the following is a full, clear, and exact description thereof, which will enable others skilled in the art to make and use the same, reference being had to the accompanying drawings, forming part of this specification,

This invention relates to a new and useful device to be applied to male and female garments, for the purpose of giving fullness to the same. The invention is more especially designed for giving fullness to the chest of male wearers and to supersede the use of padding in the upper part of the fronts of vests, and also to give prominence to the waists of ladies' dresses in front of the breasts. The invention is a modification of and an improvement upon a patent granted to us December 11, 1866. This patented article now has a ready sale, and, as artificial breasts, is far superior to anything in the market. Our within-described improvement renders the invention far more valuable by extending its use or application. This result is attained by having the swaged wire cloth or wire gauze divided into two parts, and connected when necessary by hooks and eyes, slides, or elastics, so that they may be attached to or inserted in the garment. In the accompanying sheet of drawings—

Figure 1 is a view of a female having our invention applied to it.

Figure 2, a detached front view of the same.

Figure 3, a side view of one of the parts of the same.

Similar letters of reference indicate like parts.

The device is composed of two parts A A, constructed of wire gauze or wire cloth swaged with a prominence or protuberance, *a*, of such form as to correspond to a proper fullness of the chest or breast. These parts may be inserted in the bosom of the waist of a ladies' dress between the lining and the exterior fabric, or they may be secured to the outer side of the lining and connected by hooks and eyes *b*, slides, or elastics, shown in red, fig. 2. By this modification, which renders the device capable of being attached to the dress so as to form a part thereof, it cannot get out of proper position, and is far superior to padding, being cool, and not preventing, when applied to ladies' dresses, the development of the natural breasts, the non-development of these parts being an objection attending padding or wadding. For gentlemen's vests they are also superior to padding, as they are flexible, permit of a free ventilation, and will retain indefinitely their proper shape.

Having thus described our invention, we claim as new, and desire to secure by Letters Patent—

The two wire gauze or wire cloth parts A A, swaged each with a protuberance, *a*, and in such a form as to admit of being inserted in or attached to the garment, substantially as and for the purpose set forth.

We also claim the connecting of said parts together by hooks and eyes, slides, elastics, or other fastening which will admit of said parts being connected and disconnected with facility and still keep the parts in proper position, substantially as described.

JOHN STADERMANN,
HENRY SAUERBIER.
